UNITED STATES PATENT OFFICE.

JASPER STANLEY WINGET, OF YORK, PENNSYLVANIA.

CHILD'S FOLDING COMBINED BED AND COOP.

1,340,694.

Specification of Letters Patent. Patented May 18, 1920.

Application filed January 7, 1919. Serial No. 270,036.

To all whom it may concern:

Be it known that I, JASPER STANLEY WINGET, a citizen of the United States, residing at York, in the county of York, and 5 State of Pennsylvania, have invented certain new and useful Improvements in Children's Folding Combined Beds and Coops, of which the following is a specification, reference being had therein to the accompanying 10 drawing.

This invention relates to improvements in a child's folding combined bed and coop, and the primary object of which is to provide a folding and readily transportable construction adapted to be easily converted into either a bed or a coop, or playing inclosure for the child.

The objects of the particular construction will appear from the following description.

20 In the accompanying drawings—

Figure 1 is a perspective view of my improvement, showing it assembled for use as a bed.

Fig. 2 is a view showing the device folded 25 and packed, ready for convenient transportation and handling.

Fig. 3 is a vertical transverse sectional view on the line 3—3 of Fig. 1.

Fig. 4 is a sectional view on the line 4—4 30 of Fig. 2.

Fig. 5 is a vertical transverse sectional view of the lower end of the structure, showing it assembled for use as a playing inclosure or coop for the child.

35 Fig. 6 is a detached perspective view of the combined bed spring and inclosure or coop bottom.

Fig. 7 is a sectional view on line 7—7 of Fig. 2, showing one edge of the folded structure.

My improved folding combined bed and play inclosure for children, comprises two side frames 1, which are provided with fine wire netting 2. The ends 3 of the device are 45 composed of two frames 4, which are likewise provided with wire netting. The edges of these frames 4 are hinged at 5 to the ends of the side frames 1, and the adjacent inner edges of the frames 4 are hinged together at 50 the point 6. The side frames 1 are preferably provided with supporting legs 7 for the purpose of supporting the device a short distance above the floor.

A suitable mattress 8 is provided for the 55 bed and this mattress rests upon a suitable wire spring 9. This wire spring 9 is car-

ried by a combined bottom spring member 10, which is provided with projecting edges 11, to which the spring 9 is attached, forming a recess 12, separating the spring 9 from 60 the bottom 13.

The combined bottom and spring 10 is placed in the position shown in Figs. 1 and 3, when the device is to be used as a bed. When the device is to be used as a play 65 inclosure or coop for the child, the member 10 is turned over so that the part 13 will form a bottom for the inclosure, making a play place for the child and protecting it from harm or injury, and from wandering 70 around.

The member 10 is provided with projecting pins or other suitable projections 14, which rest upon the lower part of the side frames 1, when it is used as a play inclosure 75 or coop for the child, as shown in Fig. 5, and these projections 14 rest upon suitable projections 15 carried by the side frames 1, when the member 10 is with its spring upward and in position to receive the mattress 80 8.

The object of having the projections 15 is to have the mattress near the top of the structure where the child can be readily placed thereon or removed therefrom. Of 85 course the projections 15 may be further removed from or nearer to the top of the device, and these projections may be made adjustable in any well known suitable manner for that purpose.

90 Preferably, the wire netting is sufficiently fine to protect the child from flies and other insects, especially when being used as a bed, and in this instance an ordinary mosquito netting (not shown) will be laid upon the top of the device in the ordinary well-known way to cover the child when asleep.

It will be noted that the hinges 5 and 6 are so positioned and inserted into the side and end frames that the edges of the frames 100 practically meet. This is for the purpose of making the device fly-tight when it is desired that it should be so.

105 For the purpose of readily assembling and holding the parts in their assembled position, the combined bottom and spring 10 is provided at one edge with hooks 16, which will fit over the edge of the side frames 1, as shown in Figs. 2, 4 and 7, and the mattress 8 is likewise provided with hooks 17, which 110 fit over the edge of the part 1 when the parts are assembled in position, as shown in Figs.

2 and 7. The hinges 5 and 6 permit the side frames to fold inward, as shown in Fig. 2, and thus makes a compact bundle when the parts are folded, and when so folded they 5 are readily held in their folded positions by a single strap.

Having thus described my invention, what I claim and desire to secure by Letters Patent is—

- 10 1. A closely folding combined bed and playing structure, comprising two side frames and two pairs of end frames, the end frames hinged together to fold inward and their outer ends hinged to the end frames to fold inward to permit the end frames and side frames to lie against one another in parallel planes, a rigid detachable rectangular bottom having one side solid and a wire mattress at its opposite side 15 supported away from its solid side, the bottom having outwardly projecting supporting pins and the frames having horizontal ledges adapted to receive the pins when the frames are extended to rectangular positions, a removable mattress having inwardly extending substantially L-shaped hooks to engage the edges of one 20 side of the side frames when applied to their outer sides when they are in folded positions, the bottom having inwardly extending substantially L-shaped hooks to engage the edges of the opposite outer side of the side frames when so applied to the frames when they are in folded positions, and a strap for 25 encircling the frames, mattress and bottom when in their collapsed position.
- 30 2. A folding combined bed and playing structure, comprising side and end frames hinged together to fold in parallelism, a rigid detachable bottom having one side 35

solid and a recess at its opposite side formed by having at right angles to itself projecting edges for supporting a wire spring mattress away from its solid side, the edges of the bottom provided with projections for detachably supporting the bottom within the frames when the latter are expanded to a rectangular position, the parts combined for the purpose described.

3. A folding combined bed and playing 45 structure, comprising side and end frames hinged together to fold in parallelism, a rigid detachable rectangular bottom having a wire mattress side and a solid side, the bottom provided with projections for detachably supporting the bottom within the frames when the latter are expanded to a rectangular position, a removable mattress having inwardly extending substantially L-shaped hooks to engage the edges of one 50 side of the side frames when applied to their outer sides when they are in folded positions, the bottom having inwardly extending substantially L-shaped hooks to engage the edges of the opposite outer side of the side frames when so applied to the frames when they are in folded positions, and a strap for 55 encircling the frames, mattress and bottom in their collapsed position.

In testimony whereof I hereunto affix my 65 signature in the presence of two witnesses.

JASPER STANLEY WINGET.
